UNITED STATES PATENT OFFICE.

FREDERICK MEYERS, OF BROOKLYN, NEW YORK, AND MATTHIAS STOVEKEN,
OF HOBOKEN, NEW JERSEY.

HOOK AND EYE.

SPECIFICATION forming part of Letters Patent No. 484,720, dated October 18, 1892.

Application filed March 31, 1892. Serial No. 427,254. (No model.)

To all whom it may concern:

Be it known that we, FREDERICK MEYERS, residing at Brooklyn, in the county of Kings and State of New York, and MATTHIAS STOVEKEN, residing at Hoboken, in the county of Hudson and State of New Jersey, citizens of the United States, have invented new and useful Improvements in Hooks and Eyes, of which the following is a specification.

10 This invention relates to certain improvements in hooks and eyes, as pointed out in the following specification and claims, and illustrated in the accompanying drawings, in which—

15 Figure 1 represents a face view of our hook and eye as applied to a garment. Fig. 2 is a section in the plane xx , Fig. 3, showing a rear view of the hook and eye. Fig. 3 is a longitudinal section in the plane yy , Fig. 1. Fig. 20 4 is a rear view of the hook detached. Fig. 5 is a face view of the locking-plate for the hook. Fig. 6 is a transverse section in the plane zz , Fig. 5.

25 In the drawings, the letters A B indicate the two members which constitute our hook and eye. The member A embraces a hook H and a locking-plate I. The hook is formed of wire and it is provided with two penetrating-prongs $h h$, which extend from the neck h' of the hook in a direction parallel to each other, Fig. 4, and at a certain distance apart, so as to form shoulders $h^2 h^2$ at their junction with the neck h' . The locking-plate I is provided with an aperture i , and at one end of said locking-plate is formed a recess i' , while at its opposite end is formed a lip i^2 . Said recess is wide enough to admit the neck h' of the hook and it is provided with inclined sides i^3 , Figs. 30 5 and 6, which are intended to engage the shoulders $h^2 h^2$ of the hook, as shown in Fig. 4. In order to attach the hook to a fabric F, the penetrating-prongs $h h$ are passed through a bent portion f of the fabric. Then the inner end of the locking-plate I is slipped under the 45 prongs $h h$ and the outer end of said locking-plate is forced over the hook H, and when the locking-plate has reached this position the hook is drawn out over the outer end of the locking-plate, so that its neck engages the 50 recess i' of the locking-plate and it assumes the position shown in Figs. 1 and 3. When

it reaches this position, the lip i^2 projects over the ends of the penetrating-prongs $h h$ and the hook is securely locked in position.

The member B embraces the eye E and the locking-plate K. The eye E is formed with two penetrating-prongs $e e$, which extend in a direction parallel to each other and at some distance apart, Figs. 1 and 2, and the locking-plate K is provided with an aperture k , and at one end of the same is formed a hook k' , while its opposite end is provided with a lip k^2 . In order to attach the eye E to the fabric F', the penetrating-prongs $e e$ are passed through a bent portion f' of said fabric. Then 60 the inner end of the locking-plate is slipped under the penetrating-prongs $e e$ and the hook k' is depressed into the eye E, so that when the eye is drawn forward it engages the hook k' of the locking-plate and it assumes the 65 position shown in Figs. 1 and 2. When it reaches this position, the lip k^2 projects over the ends of the penetrating-prongs $e e$ and the eye is securely locked in position.

In order to detach the hook or the eye, the 70 movements above described are simply reversed—that is to say, the hook is forced back, so that the locking-plate can be slipped out over its front end, or the eye is forced back, so that it becomes disengaged from the hook 75 k' , and then the locking-plates can be taken out.

What we claim as new, and desire to secure by Letters Patent, is—

1. A hook and eye composed of the members A B, the member A being composed of a hook having two penetrating-prongs and of a locking-plate having an opening for the fabric and a recess adapted to engage the neck of the hook, and the member B being composed of an eye having two penetrating-prongs and of a locking-plate having an opening for the fabric and a hook adapted to engage the eye, substantially as described. 85

2. The hook provided with two penetrating-prongs and shoulders at the junctions of the prongs with the neck of the hook, in combination with a locking-plate having a recess adapted to engage the neck of the hook and an opening for the fabric to which the hook 90 is to be attached, substantially as described. 95

3. A hook provided with two penetrating-

prongs and shoulders at the junctions of the prongs with the neck of the hook, in combination with a locking-plate having a recess adapted to engage the neck of the hook, a 5 point-protecting lip, and an opening for the fabric to which the hook is to be attached, substantially as described.

4. An eye provided with two penetrating prongs extending parallel to each other and 10 at a small distance apart, in combination with a locking-plate provided with a hook adapted to engage the eye and with an opening for the fabric to which the eye is to be attached, substantially as described.
- 15 5. An eye provided with two penetrating

prongs extending parallel to each other and at a small distance apart, in combination with a locking-plate provided with a hook adapted to engage the eye, a point-protecting lip, and an opening for the fabric to which the eye is 20 to be attached, substantially as described.

In testimony whereof we have hereunto set our hands in the presence of two subscribing witnesses.

FREDERICK MEYERS.
MATTHIAS STOVEKEN.
